UNITED STATES PATENT OFFICE.

CHESLEY T. SMALL, OF ST. LOUIS, MISSOURI, ASSIGNOR TO FIRST NATIONAL BANK IN ST. LOUIS, OF ST. LOUIS, MISSOURI.

SQUARE-CAN-CAPPING MACHINE.

Application filed September 27, 1920. Serial No. 413,187.

To all whom it may concern:

Be it known that I, CHESLEY T. SMALL, a citizen of the United States of America, residing at the city of St. Louis, State of 5 Missouri, United States of America, have invented a certain new and useful Square-Can-Capping Machine, of which the following is such a full, clear, and exact description as will enable any one skilled in the 10 art to which it appertains to make and use the same, reference being had to the accompanying drawings, forming part of this specification.

My invention relates to improvement in 15 can capping machines and is particularly adapted for use in connection with machines of the type shown and described in application, Serial No. 321,004 of September 2, 1919.

When can capping machines of the type 20 above referred to are used to apply caps to square cans or other cans having flat sides, it has been found that the flanges of the caps and upper edges of the can are likely to bend out of a straight line. If the flanges 25 of the cap are bent outwardly and the flanges of the can bent inwardly, this occasions no difficulty. The reverse of this, however, more often occurs as the flanges of the caps are more likely to be bent inward than 30 outward and the weight of the material in the cans tends to bend the sides outward. When this latter condition occurs it will be obvious that the flanges of the cap will strike against the upper edge of the can, when the 35 cap is forced in position, thus injuring either the cap or can, or both. One of the objects of my invention is to provide simple and effective means of overcoming this difficulty by insuring the inward bending of the upper 40 edges of the can and the outward bending of the flanges of the cap. My invention also provides effective means for centering the can in the cap positioning member whether the cans are square, round or any other form.

45 In the accompanying drawings which show as much of a can capping machine as is necessary to illustrate my invention, Fig. 1 is a vertical central section. Fig. 2 is an enlarged section of one of the cap plungers. 50 Fig. 3 is a bottom plan view, partly in section, of the can positioning mechanism. Fig. 4 is a section taken on the line 4-4 of Fig. 3. Fig. 5 is a bottom plan view of one of the capping plungers, and Fig. 6 is

a diagrammatic view illustrating the operation of the device.

10 indicates a vertical rotating shaft carrying a disc 11 having formed in its edge notches 12 which, together with an attached member which will be hereinafter particularly described, forms the cap positioning means. Carried by the shaft 10 above the disc 11 is a second disc 13 in which are spring mounted capping spindle 14, operating to force the caps on the cans by means of a 60 cam track 15. The track 15 is prevented from rotating by engagement with the stationary upright 16 of the machine. A third disc 17 is carried by the shaft 10 below the disc 11 and is adapted to position the 70 cans upon can tables 18 operated by suitable lever mechanism (not shown). All the above mentioned parts are similar to those shown and described in my prior application above referred to.

75 Secured to the disc 11 is an annular member 20 preferably formed in two or more parts for convenience in application to the machine. Formed in the annular member 20 are a number of openings 21 corresponding in size and shape to the cap to be applied to the can. In the present instance these openings are shown as square. Surrounding each of the openings 21 is a downwardly extending flange 22. The upper part of the 80 opening 21 is provided with a beveled portion 23 for guiding the cap, a lower beveled portion 24 for guiding a can and a straight portion 25 connecting the bevels 23 and 24. Arranged at the center of each side of the 85 opening 21 and preferably at the point of junction of the faces 24 and 25 is a ball 26 which is adapted to project into the opening a slight distance beyond the wall 25. These balls are preferably of hardened steel 90 such as are commonly used in ball bearings. The balls 26 are held in position either by flat springs 27 or coil springs 28, the latter being placed between adjacent flanges 22.

95 Carried on the lower end of the plunger 100 spindle 14 is a plunger 30 having its lower face so arranged that the central part projects below the periphery. This is preferably accomplished by forming the lower face convex as shown at 31.

105 In the operation of my device, the cap is fed onto the upper face of the disc 20 by any suitable mechanism (not shown).

The cap 32 is positioned by the said disc 20 and the notch 12 in the disc 11 so as to be forced down upon the can 34 by means of the plunger 21. The openings 21 are 5 made of such size that the can caps will just pass through the opening without undue friction provided they retain their normal form. However, as has been heretofore pointed out angular caps of thin sheet metal 10 do not retain their form perfectly, on the contrary the lower edges of their flanges 33 tend to assume a wavy line. These portions which project outside of the normal line will, therefore, come in contact with the inclined faces 23 and retard the cap so that the lower curved face of the plunger 31 will force the central part 32 of the cap downwardly and cause it to assume a concave form as shown diagrammatically in 15 Figure 6 of the drawings. As the angle between the body and flange of the cap tends to remain a right angle, the flanges will tend to bend outwardly as shown in this figure. Actually, however, this movement of the 20 flange is limited by the vertical walls 25 so that the practical effect of the device will be to cause the flange to adhere closely to the said vertical walls 25. When the can 14 is forced upward into a cap positioning member, the balls 26 will act on the center of its sides so as to cause the 25 said sides to curve inwardly as shown in Fig. 6 and thus insure the edges passing within the flange of the cap. The form of 30 the balls is such as to prevent injury to the sides of the can, or to the flange of the cap when the cap is forced downwardly out of the device.

In addition to the function of my device 40 in preventing injury to straight sided caps and cans the yielding balls provide effective centering means for round, square or other form of can, and at the same time do not interfere with the discharge of the capped 45 can.

Having fully described my invention what I claim as new and desire to secure by Letters Patent of the United States is:

1. In a device of the class described, the 50 combination with a cap positioning member having an angular opening for the passage of a cap and adapted to receive the top of a receptacle to which said cap is to be applied, of yielding projections carried by 55 said member and positioned approximately at the central points of its sides for centering the receptacle in said opening.

2. In a device of the class described, the 60 combination with a cap positioning member having an opening provided with flat sides for the passage of a cap and adapted to receive the top of a receptacle to which the

cap is to be applied, of yielding projections situated intermediate of the length of the sides of said opening for centering the receptacle and forcing the sides thereof to curve inwardly. 65

3. In a device of the class described, the combination with a cap positioning member having an angular opening for the passage 70 of a cap and adapted to receive the top of a receptacle to which cap is to be applied, of yielding rounded projections carried by said member and positioned approximately at the central points of its sides for centering the receptacle. 75

4. In a device of the class described, the combination with a member having an opening provided with flat sides for the passage 80 of a cap and adapted to receive the top of a receptacle to which said cap is to be applied, of rounded yielded projections situated intermediate of the length of the sides of said opening for centering said receptacle and forcing the sides thereof to curve 85 inwardly.

5. In a device of the class described, the combination with a member having an opening for the passage of a cap and adapted to receive the top of a receptacle to which 90 said cap is to be applied, of spring mounted balls carried by said members and adapted to center the receptacle in said opening.

6. In a device of the class described, the combination with a member having an opening provided with flat sides for the passage of a cap and adapted to receive the top of a receptacle to which said cap is to be applied, of spring mounted balls carried by 95 said member and adapted to bear on the 100 sides of the receptacle to center said receptacle and force the sides thereof to curve inwardly.

7. The combination with a cap positioning member provided with an opening having 105 flat sides for the passage of a cap and adapted to receive the top of a receptacle to which its cap is to be applied, of a plunger for forcing the cap through said opening, 110 said plunger having its central part projecting beyond its periphery for forcing the sides of said cap outwardly.

8. The combination with a member having an opening provided with flat sides for the passage of a cap and adapted to receive the top of a receptacle to which said cap is to be applied, of a plunger for forcing the cap through said opening, 115 said plunger having a convex face for forcing the sides of the cap outwardly. 120

In testimony whereof, I have hereunto set my hand and affixed my seal.

CHESLEY T. SMALL. [L.S.]
